UNITED STATES PATENT OFFICE.

STEPHEN H. FARNHAM AND ARTHUR W. SMITH, OF NEW YORK, N. Y., AND JOSEPH PHELPS, OF BELLEVILLE, NEW JERSEY, ASSIGNORS TO REMINGTON TYPEWRITER COMPANY, OF ILION, NEW YORK, A CORPORATION OF NEW YORK.

TYPE-WRITING MACHINE.

1,073,577.

Specification of Letters Patent. Patented Sept. 16, 1913.

Original application filed January 18, 1913, Serial No. 742,786. Divided and this application filed May 1, 1913. Serial No. 764,782.

To all whom it may concern:

Be it known that we, STEPHEN H. FARNHAM, ARTHUR W. SMITH, and JOSEPH PHELPS, citizens of the United States, and residents, respectively, of the borough of Brooklyn, county of Kings, city and State of New York; borough of Manhattan, city, county, and State of New York, and Belleville, county of Essex, and State of New Jersey, have invented certain new and useful Improvements in Type-Writing Machines, of which the following is a specification.

Our invention relates to ribbon mechanism for typewriting machines and its principal object is to provide new and improved mechanism of the character specified.

To the above and other ends our invention consists in the features of construction, combinations of devices and arrangements of parts hereinafter described and particularly pointed out in the claims.

The present application is a division of our application, Serial No. 742,786, filed January 18, 1913, and while various features of our invention are applicable generally, the particular embodiment herein disclosed was more especially designed for the machine disclosed in said prior application.

In the accompanying drawings which illustrate one form of our invention, Figures 1 and 2 are respectively the front and rear portions of a fore and aft vertical sectional view of a type-writing machine embodying our invention, such parts of the machine as are not necessary to a complete understanding of the present invention being omitted. Fig. 3 is a horizontal sectional view taken on planes indicated by the broken dotted line $x-x$ in Figs. 1 and 2 and looking downward. Fig. 4 is a fragmentary right-hand end view of the upper forward part of the machine. Fig. 5 is a horizontal sectional view of the left-hand ribbon spool and the associate parts, said section being taken on a plane indicated by the dotted line $w-w$ in Fig. 1 and looking in the direction of the arrows at said line. Fig. 6 is a fragmentary face view showing the central stationary ribbon guide and associate parts.

As shown in Figs. 1 to 4 the main frame

of the machine comprises a base 1 from which rise rear posts 2, front posts 3 and intermediate posts 4, said posts 4 being connected to the associate posts 3 by inwardly curved webs or cross pieces 5. The posts or uprights support a three-piece top plate comprising a rear part 11 and two front portions or plates 12. The machine is a front-strike machine and as will be understood from Figs. 1 and 2 has a stationary upright segment 13 which provides a support for hangers 14 on which are pivoted type bars 15 each provided with a type 16 and being supported normally by a stationary rest 17. Each type bar is connected to a key lever 18 by connections comprising a link 19, a lever 20 and a second link 21. The key levers are arranged within the base 1 and are pivoted at their rear ends on a fixed fulcrum plate 22, being provided at their front ends with keys or buttons 23. The type bars when actuated coöperate with the front face of a platen 36 diagrammatically illustrated in Fig. 2, the same being mounted on a carriage (not shown) which is urged or impelled leftward by a motor or spring drum mechanism as shown in our application, Serial No. 742,786, aforesaid. Leftward movements of the carriage are controlled by escapement devices which comprise escapement wheels 52 and 53 that are operatively related to the carriage as shown in our said application. Coöperative with said escapement wheels is a feed dog 54 mounted at the top of a dog rocker 55 pivoted at 56 to ears 40^a on a stationary bracket 40. Said rocker is operatively connected by a link 57 with a crank arm 58 projecting rearward from a rock shaft 59 which is pivoted at its ends in the sides of the base 1. Near its ends said rock shaft is provided with crank arms 60 from which depend arms or links 61 supporting a universal bar 62 which underlies the key levers 18 and is operative thereby to cause the escapement devices to permit leftward step-by-step movements of the carriage. Suitable restoring springs are provided including one for the universal bar indicated at 62^a (Fig. 2), said spring 62^a being connected at one end to a crank arm 59^a on the rock shaft 59, the other end of said spring having

a stationary anchorage. Each key lever, it will be understood, actuates the escapement devices and also operates through the described connections to actuate its associate type bar and cause the same to co-act with the front face of the platen.

In carrying out our present invention two ribbon spools 411 are arranged vertically one at each side of the machine and between 10 the front corner posts 3 and the supplemental posts 4, reference being had especially to Figs. 1, 3, 4 and 5. Said spools are mounted at opposite ends of a shaft 412 which extends transversely of the machine 15 and bears on brackets or arms 413 and 414 which are secured to the frame webs 5 by screws 415. The spools are of ordinary construction comprising flanges and a connecting core piece and receive each a detachable hub 416 which is connected to the associate spool to turn therewith by slots 417 formed at the outer end of the hub, said 20 slots being engaged by lugs 418 on the spool, said lugs projecting radially inward from 25 the hole in the outer flange of the spool through which the end of the hub passes. At its inner end the hub 416 is expanded outside the spool into a flange 419 provided with crown ratchet teeth 420. The hub 416 30 is arranged between the spool and the shaft 412, bearing on the associate end portion of the shaft which is reduced as indicated at 412^a to provide a bearing surface and is further reduced and threaded at its extreme 35 end as indicated at 412^b. The left-hand threaded portion 412^b receives a thumb nut 421 which retains the spool and hub in place but permits them to turn together on and relatively to their bearing 412^a. The 40 right-hand reduced portion 412^b instead of having a thumb nut, is provided with a handle 422 which is secured in place by a hexagonal nut 423. An inking ribbon 424 is wound on the ribbon spools 411 and extends from one to the other, passing upward at each side through a hole 425 in the associate top plate section 12 and being guided over a guide bar 426 which bridges said hole and is slightly inclined inward toward 50 the middle of the machine, the ends of said guide bars being turned downward and secured in the top plate section 12. From the guide bars the ribbon extends horizontally inward and rearward and passes through 55 slots or loops 427 formed in a stationary guide frame 428 which is secured to the stationary segment plate 429 by the same screws 430 which clamp the line gage and paper guide 431 in place. The printing portion of 60 the ribbon that extends between the guide ways or slots 427 is thereby maintained opposite the printing point on the platen 36 and in position to coöperate with the types 16 when the type bars 15 are actuated. The 65 segment plate 429 is suitably secured to the

segmental type bar support 13. The central ribbon guide 428 is preferably formed of wire and at the corners of its lower end portions is bent or looped at 428^a (Fig. 6) to provide recesses for the reception of the 70 screws 430. A cross plate or washer 432 is arranged beneath the heads of the screws 430 and coöperates with the looped portions 428^a to hold the guide 428 securely in place, said guide being thus clamped by the screws 75 between the washer 432 and the lower end portion of the line gage 431. The central ribbon guide 427 stands somewhat away from the platen opposite the printing point but being of resilient wire is adapted to 80 yield or give toward the platen if there is any tautness in the printing portion of the ribbon at the type stroke. This yield or give is sufficient to prevent the type bars from being obstructed, so that adequate 85 type impressions may be made by the types through the ribbon under all conditions.

The ribbon 424 is adapted to be fed alternately back and forth from one ribbon spool to the other through the central stationary 90 guide 428 and to this end means are provided for feeding or rotating the shaft 412 from the printing key levers 18, said shaft thus becoming a power shaft and for alternately connecting the ribbon spools to be 95 turned from and by said shaft. Accordingly the shaft 412 has mounted on it near its left-hand end just inside the bracket 413 a ratchet wheel 433 provided with a hub 434 which receives a set screw 435 by which 100 the ratchet wheel is fixed to the shaft 412. The teeth of the ratchet wheel are comparatively fine and coöperative therewith is a pawl member 436 (Figs. 1-3) provided at its upper end with a pawl tooth 437 which engages the teeth of the ratchet wheel. Guiding fingers or ears 438 and 439 extend forward from the pawl member below the tooth 437 and embrace loosely between them the ratchet wheel 433 so as to prevent 105 lateral displacement of the pawl member in respect of the ratchet wheel. One of the fingers, 439, is extended around and upward at the front side of the shaft 412, coöperating with said shaft to prevent the pawl 110 member from being accidentally displaced in the plane of the ratchet wheel by being thrown backward out of engagement therewith. The pawl member or arm 436 is inclined downward and rearward and is pivotally connected at its lower end at 440 to an arm or part 441 which is adjustably connected by screws 442 and 443 with an arm or part 444 fixed to the universal rock shaft 59 and extending forward and slightly 115 upward therefrom. The screw 442 passes through a round hole in the arm 441 but the screw 443 coöperates with an elongated slot 445 in said arm, the construction being such that by loosening the screws 442 and 120 443 the arm 441 may be rotated to a position 125 in which the pawl member 436 is disengaged from the ratchet wheel 433.

443 the arm 441 may be swung to a limited extent on the screw 442 as a pivot, the two-part member 441, 444 thus providing for an adjustment of the pawl member 436 and its tooth 437 in respect of the ratchet wheel 433. The construction is such that at the operation of any printing key lever 18, causing its associate type bar 15 to print and rocking the shaft 59 to actuate the escapement devices, the outer end of the arm 411 will swing upward, lifting the pawl member 436 and causing its tooth to coöperate with the ratchet wheel 433 to turn the same and through it the power shaft 412. Thus printing key operations will act to communicate successive step-by-step turning movements to the shaft 412. A wire spring 446 secured to the arm 441 engages at its free end with the upper rear portion of the arm 436 and tends to maintain the pawl 437 engaged with the ratchet wheel 433. A weighted detent member or arm 447 is pivoted at 448 on the arm 413 and is inclined downward and forward therefrom, being provided with a tooth 449 which coöperates with the ratchet wheel 433 to prevent accidental backward rotation thereof. The hub 434 of said ratchet wheel coöperates with the bracket 413 to prevent accidental endwise displacement of the shaft 412 toward the left, while a collar 450 screwed fast or otherwise secured to the shaft at the left of the bracket 414 coöperates with said bracket 414 to prevent endwise displacement of said shaft toward the right.

In order to transmit the motion of the power shaft to the ribbon spools in alternation, devices are provided comprising sleeves 451 and 452 which are slidably mounted on the shaft 412 to the right and left respectively of the associate ratchets 420. Secured in a recess 453 in the outer end of each sleeve is a diagonally extending arm 454 provided at its outer ends with ratchet teeth 455 which are adapted to coöperate with the ratchets 420. The sleeves 451 and 452 are connected with each other by a connecting device or rod 456 which extends from one sleeve to the other, said rod being arranged or housed in a slot-way or groove 457 cut or formed in the shaft 412. The end portions 457^a of said rod are turned outward, passing through holes in the sleeves 451 and 452. The construction is such that endwise motion communicated to one of the sleeves will be transmitted through the rod 456 to the other sleeve, the rod sliding lengthwise through the groove 457 to transmit such motion. Further, the rod in coöperation with the groove 457, provides a connection between the shaft 412 and the sleeves to transmit the rotary movement of the shaft to the sleeves. The sleeves, it will be seen, are clutch members for transmitting the rotation of the shaft 412 to the spools 411 when the teeth

455 of the sleeves engage with the ratchet teeth 420 on the spools.

Devices are provided to switch the sleeves or clutch members into and out of operation, said devices comprising a switch lever 458 (Figs. 1, 3 and 5) fulcrumed at 459 on a horizontal ear 413^a bent laterally outward from the forward portion of the bracket 413. The forward arm of the lever 458 is shaped to provide a finger piece by which the latter may be shifted, and the rear arm of said lever is provided with an upstanding pin 460 which engages with a circumferential groove 462 in the sleeve 451. By switching the forward arm of the lever 458 toward the left from the positions shown in Figs. 3 and 5 the pin 460 is caused to engage with the side of the groove 462 to switch the member 451 rightward along the shaft 412, thus disconnecting said sleeve from the left-hand ribbon spool 411, while the rightward motion of said sleeve is transmitted through the rod 456 to the sleeve 452 which is thereby connected through its teeth 455 with the ratchet teeth 420 of the right-hand spool 411. It will be understood that the sleeves or clutch members 451 and 452 are definitely spaced apart by the rod 456 to an extent such that when one of them is operatively engaged with its associate ribbon spool the other is disconnected or disengaged. A detent spring 463 secured by screws 464 to the ear 413^a coöperates at its free end with a pin 465 projecting upward from the rear arm of the lever 458. The free end of the spring 463 is bent downward and pointed to coöperate with the upper end of the pin 465 which is beveled to provide two oppositely inclined faces as indicated at 466. When the parts are as in Fig. 5 the spring 100 detent 463 will coöperate with the right-hand bevel 466 to hold the clutch member 451 engaged with its ratchet, while when the lever 458 is switched toward the right the spring detent will coöperate with the left-hand bevel 466 to maintain the right-hand clutch member 452 in operative position.

In addition to the hand operated shift mechanism, devices are provided for automatically switching the clutch devices 451 and 452 into and out of operation to reverse the ribbon feed as shown in Figs. 1, 3 and 4. Said automatic devices comprise switch members or pivoted frames each composed of a cam arm 467 and a follower 468 joined by a cross bar 469, said cross bar having down turned ears 470 which receive a pivot screw 471 by which the follower is pivotally mounted on the associate frame web 5, the pivot screw 471 projecting outward from said web. Secured at the forward edge of the cross bar 469 is a rounded guide 472 over which the ribbon 424 passes upward from its spool to the frame guide 426.

The follower arm 468 extends rearward

between the flanges of the associate spool 411 and terminates in a downwardly curved end portion 473 which co-operates with the wound up portion or plies of the ribbon as clearly shown in Fig. 4, being maintained in engagement therewith through the force of gravity. The associate cam arm 467 is arranged inward on the cross bar 469 from the follower 468 and like the follower extends rearward but is outside the spool and inclines downward so that it terminates below the follower and is also off-set or bent inward at its rear portion, being provided at its free end with a cam or inclined edge 474. This cam edge faces the follower and is adapted to co-operate with pins 475 which project radially outward from the associate sleeves or clutch members 451 and 452. There are two of these pins on each sleeve arranged opposite each other, the face of each pin opposite its follower being beveled or inclined downward as illustrated at 476 and the cam edge 474 of the follower being similarly beveled. When the spool is comparatively full of ribbon as in Fig. 4 the follower will maintain the cam arm 467 raised out of the path of the pins 475. As the ribbon gradually unwinds from the spool it allows the follower to drop and the cam arm 467 will swing downward a corresponding extent. The result will be that when the ribbon is completely unwound from the spool the cam arm 467 will drop down so that the cam edge 474 will be in the path of the pins 475 and will operate to force said pins outward. This movement will be transmitted to the sleeve or clutch member and to the teeth 455 thereon, which teeth will engage with the ratchet teeth 420, thus connecting the ribbon spool with the sleeve and forcing it to turn with the power shaft. At the same time the opposite sleeve will be drawn out of operative engagement with its ribbon spool. By reason of the beveled or inclined faces 476 the pins 475 will tend to force the cam edges 474 downward toward the face of the associate sleeve and after once engaging with the cam edge will maintain it down in operative position until the reversal of the ribbon feed has been effected. It will be observed from Fig. 3 that by reason of the inward bending or off-setting of the frame webs 5 a space is provided at each side of the machine between the posts 3 and 4 so that the ribbon, the ribbon spools and the associate devices are not interfered with.

The claims in this case relate to ribbon mechanism. Such other disclosed features as are novel are claimed in the original application aforesaid or will be covered by divisional applications to be subsequently filed.

Various changes may be made without departing from my invention.

What we claim as new and desire to secure by Letters Patent, is:—

1. In a typewriting machine, the combination of ribbon carrying spools, ribbon feeding mechanism, reversing devices for said feeding mechanism, a central ribbon guide and other guides between said central guide and said spools, said other guides being connected with certain of said reversing devices. 70

2. In a typewriting machine, the combination of ribbon spools arranged below the top plate, movably mounted guides for the ribbon between the top plate and the spools, stationary ribbon side guides above the top plate, and a central guide for the printing portion of the ribbon. 80

3. In a typewriting machine, the combination of ribbon spools, a power shaft, clutch devices for alternately connecting said spools with said power shaft, and a connection between said clutch devices, said connection being carried by said power shaft and constituting the sole connecting means between said power shaft and said clutch devices. 85

4. In a typewriting machine, the combination of ribbon spools, a power shaft, clutch devices for alternately connecting said spools with said power shaft, and a connection extending from one clutch device to the other lengthwise of said power shaft and housed within said power shaft, said connection comprising the sole means for connecting said power shaft and said clutch devices. 95

5. In a typewriting machine, the combination of a pair of ribbon spools, a power shaft near the ends of which said ribbon spools are mounted, ratchets associated with said ribbon spools, clutch devices slidable on said power shaft and adapted to engage said ratchets, and a rod connecting said devices, said rod extending lengthwise of said power shaft and being slidable in a groove therein and constituting the sole connecting means between said power shaft and said clutch devices. 105

6. In a typewriting machine, the combination of a pair of ribbon spools, a power shaft for said ribbon spools, clutch devices for alternately connecting said ribbon spools with said shaft, and a device connecting said clutch devices one with the other and also connecting said clutch devices with said shaft so that they are forced to turn therewith, said device constituting the sole connecting means between said shaft and said clutch devices. 115

7. In a typewriting machine, the combination of a pair of ribbon spools, a power shaft for said ribbon spools, clutch devices for alternately connecting said ribbon spools with said shaft, and a device for maintaining said clutch devices spaced apart a definite distance so that they can be connected 120

one at a time only with their associate spools, said device also transmitting motion to said clutch devices from said power shaft, said device constituting the sole connecting means between said shaft and said clutch devices.

8. In a typewriting machine, the combination of a pair of ribbon spools, a power shaft for said ribbon spools, clutch devices, a device connecting said clutch devices one with the other and also connecting said clutch devices with said shaft so that they are forced to turn therewith, said last named device constituting the sole connecting means between said clutch devices and said power shaft, and a manual switch lever connected to one of said clutch devices and operative to connect them in alternation with their associate ribbon spools.

20 9. In a typewriting machine, the combination of a pair of ribbon spools, a power shaft on which said ribbon spools are loosely mounted, ratchet wheels each having a hub portion interposed between the associate ribbon spool and the power shaft, pin and slot connections between said spools and said hub portions, sleeves slideable on said power shaft and provided with clutching teeth, a rod connecting said sleeves, a switch lever for switching said sleeves, and a handle for turning said shaft.

10. In a typewriting machine, the combination of a pair of ribbon spools, a power shaft, ratchets associated with said ribbon spools, devices slideable on said power shaft and adapted to engage said ratchets, a rod connecting said devices, said rod extending lengthwise of said power shaft and being slideable in a groove therein, a ratchet wheel fixed to said shaft, printing key levers, and an actuating pawl for said ratchet wheel operative by said key levers.

11. In a typewriting machine, the combination of printing key levers, ribbon spools, a power shaft therefor, a ratchet wheel connected to said power shaft, and a pawl for said ratchet wheel operative by said printing key levers, said pawl being provided with devices which loosely embrace said ratchet wheel and prevent lateral disengagement of said pawl therefrom and being further provided with a device which prevents disengagement from said ratchet wheel by a movement in the plane thereof.

55 12. In a typewriting machine, the combination of ribbon spools, a power shaft therefor, a ratchet wheel connected to said power shaft, printing key levers, a pawl for said ratchet wheel, a rock shaft, a universal bar connected to said rock shaft and operative by said key levers, and a two-part crank arm on said universal bar, the parts being adjustable, said pawl being pivotally connected to said crank arm.

65 13. In a typewriting machine, the combi-

nation of ribbon spools, a power shaft therefor, a ratchet wheel connected to said power shaft, printing key levers, a pawl for said ratchet wheel, a rock shaft, a universal bar connected to said rock shaft and operative by said key levers, a crank arm rigid on said universal bar, and a second arm on which said pawl is pivoted, said second arm being adjustably secured to said crank arm by two screws, one of which engages an elongated hole or slot in said second crank arm.

14. In a typewriting machine, the combination of a main frame comprising a base and a plurality of posts rising from said base at each side thereof, two of the posts at each side being connected by a cross bar or web, brackets secured to said webs, a ribbon power shaft journaled on said brackets, ribbon spools, and means mounted on said brackets for alternately connecting said ribbon spools to turn with said shaft.

15. In a typewriting machine, the combination of ribbon spools, a power shaft, clutch devices for alternately connecting said spools with said shaft, and means for automatically switching said clutch devices, said means including a pair of pivoted frames each comprising both a follower co-operating with the ribbon when wound on the spools, and also a cam co-operative with a pin on one of said clutch devices to switch said clutch devices.

16. In a typewriting machine, the combination of ribbon spools; a power shaft; clutch devices for alternately connecting said spools with said shaft; and means for automatically switching said clutch devices, said means comprising pivoted cam members controlled by the portions of the ribbon wound on the spools, and pins on said clutch devices co-operating with said cam members, said pins being beveled so as to insure the proper engagement of said cam members therewith, said cam members operating to cam said pins and switch said clutch members.

17. In a typewriting machine, the combination of ribbon spools; a power shaft; clutch devices for alternately connecting said spools with said shaft; and means for automatically switching said clutch devices, said means including a pair of pivoted frames each of which comprises a follower co-operating with the ribbon when wound on the spools, and a cam co-operative with a pin on one of said clutch devices, said frames also being provided with guides for the ribbon.

18. In a typewriting machine, the combination of ribbon spools; a power shaft; connected clutch devices for alternately connecting said spools with said shaft; and means for automatically operating said clutch devices, said means comprising pivot-

ed frames each consisting of a cross bar and two parallel arms, one arm lying between the flanges of the associate spool and engaging the ribbon wound thereon, and the other arm being outside of the spool and provided with a cam coöperative with the associate clutch device to shift the same.

Signed at the borough of Manhattan, city,

county and State of New York, this 30th day of April, 1913.
